238,850

OIL CHANGING WRENCH

Steven R. Jensen, Brooklyn Park, Minn., assignor to
J-Mark Quality Products, Inc., Minneapolis, Minn.

Filed Feb. 13, 1975, Ser. No. 549,758

Term of patent 14 years

Int. Cl. D8—05

U.S. Cl. D8—22

FIG. 1

FIG. 2

FIG. 3

FIG. 4

FIG. 5

FIG. 1 is a front elevational view of an oil changing wrench embodying my new design;
FIG. 2 is a side elevational view thereof;
FIG. 3 is an opposite side elevational view thereof;
FIG. 4 is an end elevational view thereof, and
FIG. 5 is an opposite end elevational view of the same.

A rear elevational view thereof is substantially a mirror image of that shown in FIG. 1.

I claim:

The ornamental design for an oil changing wrench, as shown and described.
